(57) **CLAIM**

We claim the ornamental design of a retractable aquarium spout, as shown and described.

DESCRIPTION

FIG. 1 is a perspective view of a retractable aquarium spout in a fully retracted and on position embodying the invention.

FIG. 2 is a front view of the retractable aquarium spout of FIG. 1.

FIG. 3 is a rear view of the retractable aquarium spout of FIG. 1.

FIG. 4 is a first side view of the retractable aquarium spout of FIG. 1.

FIG. 5 is a second side view of the retractable aquarium spout of FIG. 1.

FIG. 6 is a top view of the retractable aquarium spout of FIG. 1.

FIG. 7 is a bottom view of the retractable aquarium spout of FIG. 1; and,

FIG. 8 is a perspective view of the retractable aquarium spout in a fully extended and on position.

The retractable aquarium spout being transitional between the arrangement of FIGS. 1 and 8. The broken lines shown in the drawings are for the purpose of illustrating portions of the retractable aquarium spout and form no part of the claimed design.
